UNITED STATES PATENT OFFICE.

EDGAR W. ABBOT, OF BROOKLYN, ASSIGNOR TO O. A. GAGER & CO., OF NEW YORK, N. Y.

DESIGN FOR A RECEPTION-PLATE.

SPECIFICATION forming part of Design No. 21,498, dated April 26, 1892.

Application filed March 2, 1892. Serial No. 423,534. Term of patent 7 years.

To all whom it may concern:

Be it known that I, EDGAR W. ABBOT, a citizen of the United States, residing at Brooklyn, Kings county, and State of New York, have invented and produced a new and original Design for Reception-Plates, of which the following is a specification, reference being had to the accompanying drawings, forming part hereof, wherein—

10 Figure 1 is a top view of the plate embodying my design. Fig. 2 is a longitudinal section on the line $x-x$, Fig. 1.

This invention relates to a new form or configuration of plates known as "reception-plates," and also to the new ornamentation or 15 decoration of the surface of such plates.

The principal features of my design are the configuration of the rim of said plates into substantially an 8-like shape, or, more correctly, into substantially the shape of two 20 arcs of circles of different diameters meeting in a rib or raised ledge lying between the circles, of which the arcs are a part, and also the surface decoration of said plates with ornamental dashes, ribbon-like ornaments, and 25

spirals, substantially as shown in the accompanying drawings, and as hereinafter more particularly described and claimed.

In the drawings the body of the vessel is shown divided into two substantially circular portions b and c , the arcs of whose circumferences being of varying radii and the general configuration of the dash being 8-shaped. These circular portions b c are united at a point between their centers in a rib or elevation d . Upon the surface of the plate and near its edge are placed alternate dashes e and ribbon-like ornaments f . Across or near the rib or projection d are surface decorations consisting of elongated ribbon ornaments g and spirals h , arranged substantially as shown at Fig. 1 of the drawings.

What I claim is—

The design for a plate, substantially as shown.

EDGAR W. ABBOT.
